DESIGN FOR A SEAL-PRESS.

SPECIFICATION forming part of Design No. 13,897, dated May 8, 1883.

Application filed March 10, 1883. Term of patent 7 years.

UNITED STATES PATENT OFFICE.

R. HALE SMITH, OF SPRINGFIELD, MASSACHUSETTS.

DESIGN FOR A SEAL-PRESS.

SPECIFICATION forming part of Design No. 13,897, dated May 8, 1883.

Application filed March 10, 1883. Term of patent 7 years.

To all whom it may concern:

Be it known that I, R. HALE SMITH, a citizen of the United States, residing at Springfield, in the county of Hampden and State of Massachusetts, have invented and produced a new and original Design for Seal-Presses, of which the following is a specification and description, reference being had to the accompanying illustrations, forming part thereof.

10 Figure I represents a front and side perspective view of a seal-press made according to my design, and Fig. II represents a rear and side perspective view of the same.

The leading feature of my design is the peculiar form of the arm, which projects upward and forward from the base, and the same being provided with two longitudinal ribs on each side thereof, with a longitudinal cavity between them, the portion of the arm which 20 contains the plunger being of a general cylindrical form in a vertical direction, and the upper portion, in connection with the pivoted end of the operating cam-lever, being of a cylindrical form in a horizontal transverse direction.

25 In the illustrations, 2 represents the base of a seal-press made according to my design, from which the curved arm 3 extends upward and forward, in the front part of which is contained the plunger, and this part (shown at 6) is of cylindrical form in a vertical direction, as shown

clearly in Fig. II, and in the upper part of which is pivoted the operating cam-lever 9; and this upper front portion, 8, of the arm, together with the pivoted end of said lever, is of a general cylindrical form in a horizontal transverse direction, as shown clearly in the illustrations. A curved rib, 4, extends from a point just in rear of this upper transverse cylindrical part on each side, at the back edge of the arm, downward and backward to the base, and another rib, 5, extends along the front edge of the arm on each side from the base, upward and forward, to a point on the arm about opposite the termination of the back rib, 4. A deep depression is made in each side of the arm between and 45 extending the entire length of these ribs 4 and 5. The front edge of the arm, between the base 2 and that cylindrical portion, 8, which contains the plunger, is made nearly in the arc of a circle, and the operating cam-lever 9 is made 50 in the form of a reverse curve on both its edges.

I claim—

The design for a seal-press, substantially as herein described, and shown in the accompanying illustrations.

R. HALE SMITH.
